Design No. 12,078, dated December 28, 1880.

Cut 240.

UNITED STATES PATENT OFFICE.

H. CLAY BASCOM, OF TROY, AND TOBIAS S. HEISTER, OF LANSINGBURG,
ASSIGNEES TO THE N. S. VEDDER PATTERN WORKS, BASCOM, GALBRAITH
& CO., OF TROY, NEW YORK.

DESIGN FOR A STOVE.

SPECIFICATION forming part of Design No. 12,078, dated December 28, 1880.

Application filed November 24, 1880. Term of patent 3½ years.

To all whom it may concern:

Be it known that we, H. CLAY BASCOM, of the city of Troy, in the county of Rensselaer and State of New York, and TOBIAS S. HEISTER, of Lansingburg, in said county and State, have jointly invented a new and original Design for Box-Stoves, of which the following is a specification, reference being had to the accompanying cut, print, or engraving of a stove 10 having our said new design.

The design for the compound panel-ornament A consists of the oblong arched tablet b, having parallel, or nearly parallel, top and bottom sides, c d, and double convexly-curved 15 ends e e, forming the inturned angles f, and also with the sides c d, the two spreading curved points g g, the surrounding outer fillet, h, and inner scallop edging, i, and the end ornaments, j, projecting from the said inturned 20 end-angles, f, the whole being shaped, disposed, and combined as represented in the accompanying print.

The design for the lower and end portions of the side plate consists of the ornamental 25 base-part, B, with the middle stand, k, having thereon the representation of a horse and rider, l m, and the end stands, n n, each having thereon the representation of a stork-like bird, o, with overhanging plants or grasses, p, all 30 shaped, placed, and combined so as to present substantially the appearance presented by the accompanying engraving.

The design for the lower and upper portions of the end door consists of the ornamental 35 bottom portion, C, having the raised middle

ornamental part, q, and elevated side parts, r r, and the pendent corner curtain-like ornaments s s, all having the ornamental outline shapes and arrangement represented in the accompanying cut.

The design for the legs consists of the representation of a stork-like bird, t, having its head turned backward and standing on a bracket, u, with overhanging pendants v and side scrolls, w, all shaped and arranged together upon the swelling part, as represented in the aforesaid print.

What we claim as our invention, is—

1. The design of the panel-ornament A, composed of the parts b c d e f g h i j, all shaped 50 and combined as set forth.
2. The design for the lower and end portions, consisting of the parts B k l m and n o p, all shaped, placed, and combined as set forth.
3. The design for the lower and upper portions of the end door, consisting of the parts C q r r and s s, all shaped and arranged as set forth.

4. The design for the legs, composed of the parts t u v w, all shaped and arranged as set 60 forth.

In testimony whereof we hereunto set our hands, in the presence of two subscribing witnesses, this 22d day of November, 1880.

H. CLAY BASCOM.
TOBIAS S. HEISTER.

Witnesses:

JAMES A. GILMAN,
CHESTER BASCOM.
